PUNCHING MACHINE

Theodore Kaseberg, Granite City, Ill., assignor to
American Car and Foundry Company, New
York, N. Y., a corporation of New Jersey

Application December 19, 1931, Serial No. 582,056

19 Claims. (Cl. 164—90)

This invention relates to punching machines and more particularly to machines adapted to punch the required rivet holes in various shapes of bars, referred to in the steel industry as 5 "sections."

It is one of the objects of the invention to provide a machine having a characteristic of flexibility permitting its use in connection with a wide range of different shapes of bars and 10 further permitting its adoption or conversion to the punching of plates of large area. This provides a machine which may have practically continuous use rather than, as in the prior art, one which is limited to the punching of one 15 or two shapes and must stand idle when these shapes are not in demand.

In the manufacture of rolling stock for railroads a definite shape of center-sill section has been adopted as standard equipment for certain 20 types of cars. This is known as the A. R. A. center-sill section and in shape is substantially a three-fourths I-beam; that is, it comprises a vertical web with bottom flanges on each side of the web and a single slightly narrower flange 25 at the top of the web. Such a section has presented punching problems in connection with known machines. The prior art contains machines for punching channels, other machines for punching single Z-bars and still others for 30 the punching of bars generally of simple shapes. The A. R. A. car center-sill section cannot be accommodated on any of these machines in a single operation. It might, for example, be arranged on a channel punching machine of the type shown in the patent to Stevenson, No. 35 1,164,027 for the punching of the web and both flanges on one side of the web, but the section would then have to be removed and passed through another machine for punching the opposite-side narrower flange. Furthermore, these 40 center-sill sections are usually required in pairs, one right and one left, so that in arrangement in the car the top flanges are disposed toward each other. This, with machines previously 45 used, would require at least four punching operations each involving the passing of the complete bar. By the present invention a pair of car center-sill sections may be completely punched in one feeding operation.

50 Another object of the invention is to provide a machine which is adapted to operate simultaneously on a plurality of bars of the same or different shape and which contemplates the conversion of the machine, without labor of consequence, to the handling and punching of

metal plate or sheet of considerable dimension.

A still further object of the invention is to provide a compact and practical arrangement of a series of sets of dies and cooperative punches, both vertical and horizontal, in which each set of the series comprises a plurality of selectively operable punches so that holes of different diameters can be punched in the web or any of the flanges of the work piece without requiring another passage of the work through 10 the machine.

As a result of the invention a machine is produced which will effect the requisite perforation in one feeding operation of the more intricate standard sections as well as the simpler 15 sections and which by reason of its ready conversion to the punching of large plates has a universal characteristic adapted to keep it in almost continuous use.

The invention accordingly consists in the various features of construction, combinations of elements and arrangements of parts exemplified by the construction hereinafter set forth and the scope of the application of which will be indicated in the appended claims.

In the drawings, wherein is shown one of various possible embodiments of the invention:

Figure 1 is a side view of a punching machine embodying the invention;

Fig. 2 is a one-half plan view of the lower 30 plate B which carries the horizontal punches, certain parts being shown in section, the section being taken substantially on line 2—2 of Figure 1. It is to be understood that the other half is in all respects substantially the same as the 35 part shown except that the actuating device for the work feed is not duplicated on the other half of the machine;

Figs. 3 and 4 conjointly represent a bottom plan view of one-half of the upper plate which 40 carries the vertical punches;

Fig. 5 is a view in cross section taken on the line 5—5 of Figs. 2 and 3;

Fig. 6 is a view in cross section taken through the lower horizontal punches, the section being 45 taken substantially on the line 6—6 of Figs. 2 and 3;

Fig. 7 is a view in cross section showing the upper horizontal punching means, the section being taken substantially on the line 7—7 of 50 Fig. 2;

Fig. 8 is a view in cross section taken on the line 8—8 of Fig. 2;

Fig. 9 is a view in cross section taken on the line 9—9 of Fig. 2;

Fig. 10 is a view in vertical cross section taken through the upper and lower plates and along the line 10—10 of Figs. 2 and 3;

Fig. 11 is a view in vertical cross section showing the gag actuating mechanism for certain of the vertical punches, the section being taken along the line 11—11 of Fig. 4 and also along the line 11—11 of Fig. 3;

Fig. 12 is another sectional view of the gag actuating mechanism shown in Fig. 11, the section being taken along the line 12—12 of Fig. 4;

Fig. 13 is a fragmentary view in plan, indicating one of the modifications made to convert the machine to plate punching;

Fig. 14 is a view in cross section taken on the line 14—14 of Fig. 13;

Fig. 15 is a view in front elevation with parts of the base and superstructure omitted.

Reference is made to the above-mentioned patent to Stevenson and also to his patents numbered 1,164,026 and 1,164,028 for purposes of comparison and determination of the character and scope of the present invention. It should be noted that in substantially the time required for the passage of one bar through a punching machine a pair of car center-sill sections are completely punched not only with aligned holes through the web and all of the flanges, but with web holes out of alignment and with the perforations either in the web or the flanges being of different diameters if desired.

Referring now more particularly to the drawings and to the:

35 Construction of the machine in general

A heavy duty multiple punch A has a base 10, spaced side housings 11 connected by a top cross beam 12 which carries the bearings for an operating shaft 13. The punch has upper and lower jaws 14 and 15 respectively and a punch slide 16 mounted for reciprocation in the side housings and a consequent up-and-down movement in the vicinity of the upper jaw 14. Fixed in the lower jaw 15 is a bed plate 17. The construction as thus far described, together with the operating motors, power transmitting devices, eccentric 18 and connections between the eccentric and slide 16, are all of conventional design.

Although the work may be fed through the machine by hand, nevertheless it is preferred to use one of the various conventional automatic work feed devices such as indicated at 19. As is well known such a device may be a simple friction feed of the work against limiting stops or it may involve automatic spacing arrangements, or templates, or both. Insofar as the present invention is concerned the particular type of automatic feed is unimportant.

60 The upper and lower punch-and-die plates and associated mechanism

A lower plate or table B is securely bolted to the bed plate or block 17 and remains fixed throughout the operation of the machine. An upper plate C is securely bolted to the bottom face of slide 16 and reciprocates therewith. At the rear it carries fixed brackets 20 pivotally connected to arms 21 which have their rear ends 22 arranged by pin and slot connections 23 with ears 24 projecting rearwardly from the opposite side housings 11. The arms 21 accordingly have pivotal movement from their rear ends in accordance with the up-and-down movement of the slide 16 and the upper plate C fixed thereon.

The purpose of this movement will be described later.

The lower plate or table B has rearward extensions on opposite sides of the center line, one of which is indicated at 30. These are suitably connected with pedestals 31, the upper ends 32 of which are bolted to extensions 33 on the main frame of the punch A. This provides additional support and reinforcement for the rear portion of the table B which overhangs the bed 10 plate 17.

The lower plate and associated mechanism

The lower fixed plate or table B is of generally rectangular form and has arranged thereon 15 on each side of its transverse center line a series of dies.

Commencing at the forward end of the machine (see Fig. 2) the first set of one series is indicated at 40. The dies 41 are vertically disposed and are of different diameters. They are set in a die-block 42 which is fixed on the table B by a T-bolt 43 and nut, the bolt being arranged in slot 44 allowing for rearrangement between successive operations if desired. The rear end of the block 42 is shouldered at 45 and held in position by a shoulder block 46 bolted to the table B as indicated at 47.

The second die set is shown in Fig. 2 at 48 comprising a slideable die-block 49 containing 30 a pair of different sized vertically arranged dies 50. This die-block is arranged in a T-slot 51 cut in the table B and is movable to various positions longitudinally of the table and laterally of the work by reason of its connection 35 with a rack bar 52 meshing with a gear 53. The gear 53 is rotated from a hand wheel 54 through a pinion 55 cut in the lower end of a vertical sleeve 56. This pinion meshes with a gear 57, mounted for rotation on a stud 58 projecting from the upper surface of the table B, and which in turn meshes with the gear 53 also loosely mounted on a similar stud 59 set in the table. As shown clearly in Fig. 5 of the drawings, the sleeve 56 is extended vertically 45 above the hand wheel 54 a considerable distance and on this extended portion, gear teeth 60 are cut and meshed with a gear 61 so that a rack bar 62 is driven through a train of gearing attached to the lower face of the upper plate C 50 for the purpose of moving an adjustable punch block in the upper plate in synchronism with the movements of the adjustable die-block in the fixed table. The sleeve 56 is rotatively mounted 55 on a spindle 64, the lower end of which is fixed in the table B.

The two die sets 40 and 48 are for cooperation in the punching of holes in the web of the work.

The next set of dies is for cooperation in the punching of the flanges of the web. For this purpose a guide-block 70 is secured in position on the top surface of the fixed table B. This guide-block has an exterior configuration in cross section corresponding to a channel-shaped portion of the work to be punched, so that in passing through the machine the bar lies with its web in a horizontal plane, one of its lower flanges and the opposed top flange projecting downwardly over the slightly tapered walls of the guide-block 70 (see Figs. 6 and 7). The forward end of the guide-block 70 is provided with sets of horizontally arranged dies 71 and 72 oppositely faced to contact with the inner faces of the flanges as the work passes over the block. Inasmuch as the single flange 75

of the work may be somewhat narrower than the correspondingly projecting lower flange the spacing of the rivet holes therein may be nearer the web than is the case with the wider flange. The die set 72 is therefore in a horizontal plane slightly higher than that of the die set 71. Toward the rear of the block 70 in the direction of passage of the work, a die-block 73 is arranged above the level of the horizontally disposed web of the work. This block is supported by a frame 74 comprising a cast plate 75 keyed and bolted in position on an upper face 76 of table B, and spaced bars 77 connected to the casting 75 as indicated at 78, which bridge a gap between that casting and a punch-block-carrier slide 79 which is keyed and otherwise suitably secured to the table B. The bars 77 are attached to the punch-block-carrier slide 79 by bolts 69. The die-block 73 is suitably secured in the frame 74 and reinforced against punch thrust by the substantially heavy casting 75. This block contains a set of two horizontally arranged dies 80, the level of which is above that of the other horizontal dies and above the web of the work in its passage over the guide-block 70 and between that block and an extension 81 of the supporting casting 75. These dies therefore cooperate in the punching of the upwardly extending flange of the work as it passes through the machine with its normally vertical web arranged in horizontal position.

As shown clearly in Figs. 2, 6 and 10 of the drawings, provision is made for the exit of punched slugs from any of the die-blocks mentioned. The table B is slotted at 90 to release slugs from the fixed die-block 42. It is slotted at 91 to release slugs from the adjustable die-block 49. The guide-block 70 is interiorly apertured at 92 and the table B is apertured at 93 to release the slugs in horizontal lower punching. In the upper horizontal punching operation a strap 94 is apertured to permit horizontal ejection of the slugs onto the top surface of casting 75 until they fall through registered openings 95 in the frame 74 and table B.

In addition to carrying certain sets of dies as just described, the lower plate or table B also carries the horizontal punching devices for perforating the flanges of the work. These are arranged in six sets, one set comprising the sliding punch-block-carrier 100, having mounted therein a pair of punches 101 of different diameters and the carrier being slidably mounted in machined ways in the top of the table B. Another set comprises the sliding punch-block-carrier 102 having mounted therein a pair of punches 103 of different diameters and being arranged in machined ways in the top of the table B so that the punch-block-carrier 102 is in lateral alinement with the punch-block-carrier 100 and the movements of their corresponding punches are opposed. As will be apparent from the previous description of the die arrangement in the guide-block 70, the arrangement of punches 103 may be on a horizontal level slightly above the punching line of punches 101 but still below the top of the block 70 and in position to perforate a flange of the work which extends downwardly from the web. Similar sets of punch blocks and punches are arranged on the other side of the machine so that with respect to this particular type of horizontal punching there are four sets of punches arranged in alinement.

Referring particularly to Figs. 2 and 7 of the

drawings, an upper set of horizontal punches is shown at 104 in a punch block 99 fixed in a carrier 105 which in turn is arranged in ways formed by the side and bottom walls of punch-block-carrier slide 79. These punches cooperate with the dies 80 in die-block 73 to perforate flanges extending upwardly from the horizontally disposed web of the work. The line of punching is, therefore, above the top surface of the guide-block 70 and above the horizontally disposed web. A similar set of punches with punch-block, carrier and slide is arranged at the opposite end of the table B.

The actuating means for the horizontal punches

The horizontal punches are all actuated from the upper plate C by toggle devices which are generally similar in action though differing slightly in details of construction. The toggles for operating the forward and lower sets of horizontal punches are substantially identical, each comprising an arm 110 pivotally secured at 111 to a bracket 112 bolted to the underside of the movable plate C. The arm has an arcuate end 113 bearing on a stud 114, the end being interlocked with the stud by flanges one of which projects laterally into a circular groove 115 in an enlarged head 116 of the stud. A similarly grooved cap 109 is fitted over the opposite end of the stud engaging another lateral flange of the arm and is held in position by threads 117. Further making up the toggle are the arms 118 and 119 each having arcuate ends bearing against the stud 114 and outwardly extending flanges on either side fitting respectively the circular grooves in the enlarged head 116 and cap 109. The arm 118 is pivotally connected at 120 in an upstanding wall 121 integral with the table B. The arm 119 is pivotally connected to the punch-block-carrier 100 as indicated at 122. The toggles at either end of the table have their arms 118 connected in the walls 121 as described but the corresponding arms of the central toggles react against each other by an engagement with a stud 123 substantially in construction and assembly like the studs 114.

By these toggle constructions downward movement of the slide 16, carrying with it the plate C, causes the punch-block-carriers of each series to move toward each other until the punches perforate the flanges of the work and enter the dies. As the table C retreats the toggle arms are brought together causing the punch-block-carriers to withdraw to their original positions.

The rear or upper horizontal punches have a slightly different toggle arrangement in that the connection of an arm 125 corresponding to any of the arms 110 of the actuating means of the lower horizontal punches is connected to the rocker arms or beams 21 by a universal connection 126, rather than to the upper plate C. As previously described these arms are fixed at their inner ends to the upper plate C and move conjointly therewith so that any movement of the lower horizontal punch toggles must be accompanied by similar movement of the upper ones.

The horizontal punches and the dies shown in Fig. 2 are duplicated in the other half of the machine. The toggle for the upper horizontal punch is located at the opposite end of the table and the direction of movement of the two sets of upper horizontal punches is in opposition.

The upper plate and associated mechanism

The upper plate C has fixed to the lower face thereof sets of vertical punches 130 each comprising in the present embodiment two punches of different diameters in a punch block 131, the latter being positioned by shouldered engagement with the plate as indicated at 132 and secured by a T-bolt 133 in a slot 134 in the plate. 5

10 The punches of these sets cooperate with the vertical dies 41 of the fixed die sets 40 on the lower plate or table B.

15 Each of the rack bars 62, previously mentioned, carries a punch block 136 slidably arranged in a T-slot 137 in the movable plate C. This block, in each instance, carries a pair of vertical punches 140 of different diameters which are maintained in cooperative relation with the dies 50 of die sets 48 in the lower table, by the 20 upper and lower rack bars 62 and 52 movable back and forth in unison by the gearing previously described, under the control of the hand wheel 54.

25 A traveling rig 150, best shown in Figs. 4 and 12 of the drawings, is mounted for longitudinal movement on the plate C, that is, a movement transversely of the direction of feed of the work. This rig comprises a bracket 151 upturned at its forward end and having a sliding connection in a T-slotted plate 152 fixed to the forward edge of the plate C. The bracket 151 extends rearwardly and downwardly to a level 149 where it has bolted upon it a housing member 153. The housing is positioned directly below and 30 centrally of the rack bar 62 which carries the laterally adjustable punches 140. Bolts 154 pass through the housing 153 and tap into the rack bar 62 as clearly shown in Figs. 11 and 12. The housing 153 provides two pockets 155 and 156. 35 Within the pocket 155 a segmental or fan gear 157 is fixed on a hollow key stud 158 which also has secured to it, exteriorly of the housing, a beveled pinion 160. The stud 158 is rotatively mounted in the housing 153 and may be rotated in either direction by the beveled pinion 160. 40 The segmental gear 157 engages a rack member 161 which extends toward the center line of the machine and carries at its inner end a gag member 162 which provides for the selective operation of vertical punches 140. The said rack member carries a pointed pin 163 of a detent mechanism which also comprises a spring pressed plate 164 positioned in the pocket 156 and having three spaced indentations 165 for three different positions of the gag member. 45 As shown in Fig. 11 the gag is in neutral position whereby actuation of the plate C allows both punches 140 to recede upon contact with the work without effecting perforation. Diagonally opposite corners of the member 162 are raised at 166 and 167 to provide gags movable into and out of position between the plate C and one or the other of punches 140. The segmental gear 157 is controlled as to rotative movement by a handle 170 50 fixed on a shaft 171 journaled in brackets 172 fixed to the top surface of plate C near the forward edge thereof. The shaft 171 extends to the end of the movable plate C as shown in Fig. 4 of the drawings and there is connected by chain and sprocket transmission 173 to another shaft 174 journaled in suitable end bearings 175 on the underside of the plate C at the rear thereof. The shaft 174 is splined as indicated at 176 to allow a beveled pinion 177 to ride longitudinally thereon. This pinion is ro-

5 tatively driven by the shaft 174 and rotatively supported on a small bracket 178 fixed to a side wall of the housing 153 so as to be in a continuous mesh with the beveled pinion 160 connected to the fan gear 157. The plate 152 may be provided with suitable template indicating chart cooperative with a pointer or other mark carried by the upturned end of the bracket 150 so that the operator may readily set the moving punches across the work to desired position. 10

The splined relation of the shaft 174 and the pinion 177 allows the entire rig to be moved in accordance with actuation of the rack bar 62 so that in adjusting the vertical punches 140 the traveling rig is also adjusted and in any position of adjustment it is capable of operating the gag member 162 for selection of the proper punch. The rig and actuating mechanism as above described is duplicated on the opposite side of the 20 machine for the adjustable punches of the other series.

The various gags for selective operation of the punches

25 The gags for operating the adjustable vertical punches have already been described. Gags 180 for selective operation of the punches of fixed sets 130 each comprise a slotted plate 181 straddling the securing bolt 133 which holds the punch block 131 in position. The plate is provided with a downwardly extending handle 182 and may be slid from a position out of engagement with either of the punches of a set to inward positions over either punch.

35 The gags for the horizontal punches, which are best shown in Figs. 2, 6 and 7 of the drawings, comprise handles 190 and operating pins 191, the latter being arranged in slide bearings 192 and carrying gag blocks 193. By movement of 40 the handles the gag blocks are located in back of the punch which it is intended to operate and each gag block is backed up by a member 194 on the carrier for the punches. If desired all of these horizontal punch gag devices may be 45 equipped with detents on the general order of the one shown in Fig. 11 so that the three different positions of the gag may be quickly and accurately determined by the operator. The gags are similar for the punches of the upper 50 horizontal level as well as all of the punches of the lower lever. Another gag 200 and operating handle 201 therefor is shown at the top of Fig. 3 in the drawings. This selectively controls the operation of the automatic feed shown 55 in Figs. 1 and 2 involving a rack bar 202, gear 203, shaft 204 and transmission devices 205 connecting to a pawl and ratchet mechanism 206.

Operation

60 As an example of the operation of the machine A. R. A. car center-sill sections of right and left form are fed into the machine over the respective guide-blocks 70 on opposite sides of the center line. The fixed vertical dies have 65 been set and bolted in proper position on the table B and their cooperative punches bolted in position on the plate C. The webs of the separate car center-sill sections rest respectively on the tops of the die-blocks in each series and the 70 downward flanges straddle these blocks and also the hold-down block 46. It is usual construction to provide a large number of perforations in the web which are in longitudinal alignment. The fixed dies 41 and their cooperative punches 75

accommodate this requirement. It is also usual construction to provide a number of perforations in the web which are substantially out of this alignment and for this purpose the adjustable dies 50 and conjointly operated punches 140 are moved by operation of the hand wheel 54 to proper position laterally of the web. As the work is fed into the machine, if the first perforations required are those in alignment in the web, the pieces are stopped and the punch head or slide operated in conventional manner to cause the upper plate C to descend. The operator has previously set the gags behind the proper punches of the sets 40 according to the required diameter of the perforation. As the upper table descends these are the only punches which are active, all others, both vertical and horizontal, receding into their punch blocks, preferably, in the case of the horizontal punches at least, against the action of springs 220. For any perforations required in the web which are out of alignment with those made by the fixed punches the proper gag on plate 162, controlled by the handle 170 through the fan gear 157 and rack 161, is set in position behind one of the punches 140 according to the diameter required. The slightly tapered inner faces of the flanges on the work form with the web a tapered wall cavity fitting the work to the block 70, the opposed flanges being backed up by the walls of the block. Further feed of the sections into the machine presents the flanges opposite the sets of lower horizontal punches, all four of which may be gagged according to requirements and operated conjointly to perforate the top and bottom flange of each of the pair of car center-sill sections at the same instant.

To perforate the upwardly extending flange the section is passed with its web under the supporting and reinforcing casting which carries the die-block 73. This die-block is constructed preferably with a tapered wall which conforms to the inclined face of the upwardly extending flange. Gags 193 are moved opposite the punch of proper diameter on opposite sides of the machine. On downward movement of the slide the upper horizontal punches perforate the upper flanges of each of the right and left car center-sill sections.

It will be obvious that the machine is adapted to the punching of channel bars and other sections and that it is also possible to run through two sections of different shape at the same time, as for example, a straight channel might be passed over one set of blocks and a car center-sill section over the other, both pieces proceeding through the machine at the same time.

Converting the machine to plate punching

When it is desired to use the machine for plate punching all of the parts used in horizontal punching which extend above the level indicated in Fig. 10 by X are removed. This includes the casting 75, the casting 79, both upper horizontal punch-block-carrier slides and their actuating toggles, also the lower horizontal punch-block-carriers and the actuating mechanism therefor. The hold-down block 46 is removed and a filler block 230 shown in Figs. 13 and 14 is substituted. This substantially levels the upper surface of lower plate or table B to the plane X allowing for the handling and feeding of wide metal plate and the punching of same by any of the vertical punches heretofore described. By the T-slot mounting for the fixed

punches and dies it is possible to mount a great number of punches on the plate and the same number of cooperating dies on the table B. It is to be noted that the conjointly movable and adjustable punch and die is operative over a considerable range so that these punches and dies may be used, if desired, in the perforating of wide metal plate.

What is claimed is:

1. In a punching machine, vertical and horizontal dies mounted for the passage thereover of a horizontally disposed web having downwardly and upwardly extending flanges, vertical punches cooperative with the said vertical dies for web punching, a horizontal punch for punching a downwardly extending flange of said web, a higher horizontal punch and die for punching an upwardly extending flange of said web, toggle actuating means for the horizontal punch, and movable gags between the toggles and the punches by which they may be operated selectively.

2. In a punching machine, vertical and horizontal dies mounted for the passage thereover of a horizontally disposed web having downwardly and upwardly extending flanges, vertical punches cooperative with the said vertical dies for web punching, a pair of horizontal punches for punching a downwardly extending flange of said web, a higher horizontal punch and die for punching an upwardly extending flange of said web, toggle actuating means for the horizontal punches, one of said vertical punches being conjointly movable in a horizontal direction with its cooperative die for lateral adjustment, and a gag device between the toggle and the horizontal punches whereby either of them may be operated without operating the other.

3. In a punching machine, means for supporting a pair of spaced flanged webs for feeding movement, vertical and horizontal punches and dies arranged for punching the web and certain of its flanges, other horizontal dies arranged above and to the rear of the web supporting means and horizontal punches cooperative with the last said dies arranged for horizontal punching in opposite directions of other flanges respectively of the pair, said supporting means and said horizontal punches and dies being removable to permit the insertion of wide plates for plate punching.

4. A punching machine having a bed and a reciprocating slide, a table fixed to said bed, two series of die-blocks on said table each comprising vertical and horizontal dies, a plate fixed on the punch slide carrying two series of vertical punches, horizontally movable punches on said table cooperatively arranged with the horizontal dies of each series, connections between said plate and said horizontally movable punches, one of the horizontal dies and its cooperative punch in each series being in a plane above the perforating plane of the vertical punches and their cooperative dies, and means permitting removal of horizontal punch parts extending above said perforating plane.

5. A punching machine having a bed and a reciprocating slide, a table fixed to said bed, two series of die-blocks on said table each comprising vertical and horizontal dies, a plate fixed on the punch slide carrying two series of vertical punches, horizontally movable punches on said table cooperatively arranged with the horizontal dies of each series, connections between said plate and said horizontally movable punches,

- means permitting removal of horizontal punch parts extending above the perforating plane of the vertical punches and their cooperative dies and a filler block interchangeable with a part on said table and extending substantially to said perforating plane.
6. In a punching machine, in combination, a fixed table, a movable plate, two spaced series of die-blocks on said table each comprising sets of vertical dies, oppositely disposed lower horizontal dies and upper horizontal dies facing outwardly; means for guiding a car center-sill section through each of said series of die-blocks with its web horizontal and its flanges extending vertically below and above the web, sets of movable punches for the die sets, parts on said table which extend upwardly into the horizontal plane of the web being removable, and a filler member adapted to fit said table to fill a gap therein up to said horizontal plane.
7. In a punching machine, a pair of spaced work-supporting dies, a lower die plate supporting said dies, a pair of oppositely moving punches slidably mounted on said die plate, a toggle mechanism having an arm operatively connected to each of said punches for simultaneously operating them in opposite directions, and gags interposed between the toggle mechanisms and the punches.
8. In a punching machine, a bed plate, a vertically reciprocating punch operating member, oppositely facing horizontal dies on said bed plate adapted to support downwardly extending spaced flanges of a flanged web, another set of oppositely facing horizontal dies on said bed plate adapted to support the downwardly extending spaced flanges of another flanged web, oppositely moving punches slidably mounted between said dies and a toggle mechanism, said toggle mechanism having an upper arm connected to said reciprocating member and a lower arm connected to said oppositely moving punches, the connection between said lower arm and said punches including a gag mechanism.
9. In a punching machine, a bed plate, a vertically reciprocating upper plate, a punch carrying slide, slidably mounted on said bed plate, a second punch carrying slide mounted on said bed plate at the rear of said first named punch carrying slide, separate toggle means connected to said vertically reciprocating plate and to said punch carrying slide for operation thereof, gags between the toggles and the punches, and operating means for said gags.
10. In a punching machine, a bed plate, a vertically reciprocating punch operating member, a vertical punch carried by said punch operating member, a vertical die carried by said bed plate and cooperating with said punch, a horizontal punch and die set mounted on said bed plate and including a plurality of cooperating punches and dies, a connection from said vertically reciprocating punch operating member for operating said horizontal punches, and gag means between said connection and said horizontal punches whereby they may be selectively operated.
11. In a punching machine, a bed plate, a vertically reciprocating punch operating member, a plurality of horizontal dies carried by said bed plate, a plurality of horizontally reciprocating punches cooperating with said dies, a connection from said vertically reciprocating punch operating member for operating said punches, and gag means between said connection and
- said punches whereby the punches may be selectively operated.
12. In a punching machine having a bed of substantial width and being adapted to carry a set of vertical dies, a vertically reciprocating punch operating mechanism adapted to carry punches to cooperate with said dies, said punching machine being normally adapted for plate punching, an attachment adapted to be mounted on said bed, said attachment including horizontal die sets and horizontally reciprocating punches to cooperate with said die sets and connections between said horizontal punches and said vertically reciprocating punch operating member whereby said punching machine may be adapted for the punching of either wide plates or flanged sections.
13. In a punching machine having a horizontal bed of substantial width, and a vertically slideable punch operating member mounted above the bed, said machine being normally adapted for punching of wide plates, an attachment for converting said machine to the punching of angular sections comprising a block having a horizontal die therein and adapted to be mounted on said bed, a horizontally reciprocating punch adapted to cooperate with said die and toggle connections between said punch and said punch operating member.
14. In a device of the class described, a bed plate, a horizontally slideable die carried by said bed plate, a vertically reciprocating punch-carrying plate, a vertical punch slidably mounted on said punch-carrying plate, a vertical pinion shaft having gear teeth cut therein, gearing driven by said gear teeth for simultaneously sliding said punch and die in a horizontal direction to keep them in alignment with each other, the gear teeth on one end of said pinion shaft being of sufficient length to permit the up and down sliding movement of the punch-carrying member to be accomplished without either disengaging the gearing from the pinion shaft or changing the positions of the punch and die.
15. In a punching machine, a bed plate, a vertically reciprocable upper plate, a punch block carrier slidably mounted on said bed plate, a toggle for operating said punch block carrier, said toggle being connected to the punch block carrier, the bed plate and the upper plate, a pair of punches carried by said punch block carrier, a gag adapted to be moved into position behind either of said punches selectively, and an operating handle for said gag.
16. In a punching machine, a bed plate, a punch block carrier slidably mounted on said bed plate, a plurality of punch blocks carried by said punch block carrier, a punch carried by each of said punch blocks, spring means for yieldably holding said punches in operative position, a gag selectively movable to position behind a selected one of said punches to positively hold it in operative position, and a handle for said gag.
17. In a punching machine, a bed plate, a punch block carrier slidably mounted on said bed plate, a pair of punches carried by said punch block carrier, a reciprocating upper plate, toggle means connected between said upper plate, said bed plate and said punch block carrier, a plurality of punches carried by said punch block carrier, springs for yieldably holding said punches in operative position, a slideable gag selectively movable to position behind either of above said punches, and an operating handle for said gag.

18. In a punching machine, a bed plate, a punch block carrier slidably mounted at the rear of said bed plate, a plurality of punches carried by said punch block carrier, spring means for yieldably holding said punches in operative position, a reciprocating upper plate, an operating connection between said upper plate and said punch block carrier, a gag selectively movable to position behind a selected one of said punches, and a handle for said gag, said handle extending forwardly over said bed plate.

5 19. In a punching machine, a bed plate, a 10 5
slidable punch block carrier mounted at the rear of said bed plate, a plurality of punches carried

by said punch block carrier, spring means for yieldably holding said punches in operative position, a reciprocating upper plate, an operating connection between said upper plate and said punch block carrier, a gag selectively movable to position behind a selected one of said punches, and a handle for said gag, said handle extending forwardly between said bed plate and said upper plate.
